UNITED STATES PATENT OFFICE.

ENOS A. DE WATERS, OF FLINT, MICHIGAN, ASSIGNOR TO GENERAL MOTORS CORPORATION, OF DETROIT, MICHIGAN, A CORPORATION OF DELAWARE.

LUBRICATING MEANS FOR VALVE-OPERATING DEVICES.

1,346,116.

Specification of Letters Patent. Patented July 13, 1920.

Application filed June 25, 1919. Serial No. 306,727.

To all whom it may concern:

Be it known that I, ENOS A. DE WATERS, a citizen of the United States, and resident of Flint, Genesee county, State of Michigan, have invented certain new and useful Improvements in Lubricating Means for Valve-Operating Devices, of which the following is a specification.

My invention relates to valve operating mechanism for internal combustion engines and similar devices, and the object of my invention is to provide valve operating mechanism in which improved means are provided for lubricating the bearings thereof and in which the valve operating and lubricating functions are present and secured in a single mechanism of simple and compact construction, and one not likely to get out of order, the lubrication of the bearing thereof being accomplished automatically when the mechanism is in operation, the supply of oil being continuous and certain at such times, and all the bearings of the device being lubricated by oil derived from a single reservoir, which reservoir also acts as a support for one or more valve operating levers whereby a corresponding number of valves are operated, and the capacity of which reservoir is such that it will contain sufficient oil for lubricating the bearings for a considerable time.

The drawing accompanying and forming a part of this specification illustrates what I at present regard as the preferred mechanical form or embodiment of my invention, although the same may obviously be embodied in various other forms and constructions, all within the scope of my invention and intended to be covered by the patent to be obtained therefor, it being here expressly pointed out that my invention includes all such variations and modifications of the particular embodiment thereof illustrated as come within the scope of the concluding claims wherein the distinguishing features in which the invention consists are particularly pointed out.

In the drawing—

Figure 1 is a view partly in end elevation and partly in section showing my invention as applied to an internal combustion engine, the engine being indicated conventionally, and

Fig. 2 is a plan view upon a smaller scale

partly in section, showing an arrangement 55 of rocker arms embodying my invention.

Referring to the drawing, the reference numeral 3 designates a portion of a vertically arranged cylinder of an internal combustion engine or similar device, and 4 the 60 stem of a valve which is operated by the inner end 5 of an oscillating valve operating lever supported intermediate its ends by a suitable standard 6. The outer end 7 of this lever is operated by a reciprocating operating member shown as in the form of a tappet rod 8 having a ball-shaped upper end which fits within a socket of corresponding form provided upon the under side of the said lever and vertical movement is imparted to 70 the said tappet rod by means of a suitable cam or equivalent element, not shown.

The valve contemplated in the embodiment of my invention illustrated is of the puppet type, and a spring 9 is employed to 75 close the same and hold it normally upon its seat, although other types of valve may be employed as my invention is not limited to use with the specific kind of valve here referred to. It therefore follows that upward movement of the tappet rod 8 will be communicated to the valve, not shown, through the oscillating valve operating lever and the valve stem to thereby open the valve, the valve being returned to its seat by the 85 spring 9, as will be appreciated.

The oscillating valve operating lever or rocker arm is supported by a hollow supporting member 10, which in turn is supported by the standard 6, and which supporting member in actual practice, and assuming the invention to be applied to a multiple cylinder engine, is preferably in the form of a hollow shaft extending longitudinally of the cylinder block, from which it 95 follows that the said shaft serves as a support for the plurality of valve operating levers whereby all the exhaust, or all the supply, or all of both such kinds of valves are supported. In such a case a plurality of 100 supports such as are provided by the standard 6 will obviously be employed in order to secure a sufficiently rigid support for the shaft which supports the several valve operating rocker arms employed for operating 105 the valves, as will be understood.

The interior of the hollow supporting member or shaft 10 serves as an oil reser-

voir to which oil is supplied in any way, and by means of any suitable oil supply device; and the said shaft is provided with a number of holes, one associated with the bearing between said shaft and each rocking lever and in which holes the outer ends of wicks, one of which is shown at 11, are secured, and the inner ends of which wicks are submerged in the oil contained within the hollow rocker arm supporting shaft or support 10. Oil will therefore be supplied or fed to the bearings for the several valve operating levers by capillary action, and by means of and through the wicks, as will be appreciated. Suitable removable and renewable bushings 12 are commonly employed to reduce the friction and secure a more satisfactorily operating bearing, and the capacity of the reservoir formed by the shaft 10 is sufficient to provide for the lubrication of the entire valve operating mechanism for a considerable time.

The outer end of the valve operating lever or levers in case more than one is used is provided with a longitudinally extending passage which contains an absorbent material or member 13 such, for example, as a wick, and along and through which member oil derived from the interior of the hollow supporting member 10 is conveyed to a bearing 14 at the upper end of the tappet rod 8 and between the rounded end thereof and the wall of the socket into which said end enters, a hole 15 being provided to admit oil to the bearing, as shown. In the embodiment of my invention illustrated the upper end of the tappet rod is spherical in form and fits into a similarly shaped socket or seat provided in the under side of the rocker arm, as hereinbefore mentioned, although the particular type of bearing between the parts in question is of secondary importance, and my invention is not limited to the use of any particular type thereof. The arrangement and adjustment of the parts is preferably such that when the tappet rod 8 is in its uppermost position the inner end of the absorbent member or wick 13 will contact with the outer end of the wick 11 or absorbent member 11, so as to receive oil therefrom through capillary action, although oil will obviously be supplied to the bearing at 14 if the ends of the wicks 11 and 13 are brought opposite one another to a greater or less extent at any phase of the operation of the device, and when the parts thereof are in any position. In fact oil will be supplied to the bearing at 14 to a degree even if the said ends do not come into actual registry with one another, in which case the wick 13 derives its supply of oil from the rock shaft bearing, which bearing in turn is supplied with oil by and through the wick 11 as hereinbefore explained.

Various forms of absorbent members or

wicks may be employed in the device such, for example, as pieces of felt, woven, braided or spun fiber, etc., and the same may be made of various materials such for example as cotton fiber, asbestos or mineral wool, and in fact from any material having the qualities requisite for the end to be obtained. Also note that the oil reservoir shaft 10 may be loosely filled with absorbent material such as cotton waste, which will insure a supply of lubricant to the wicks regardless of the position of the reservoir shaft.

As changes of construction could be made within the scope of my invention, it is intended that all matter contained in the above description or shown in the accompanying drawings shall be interpreted as illustrative and not in a limiting sense.

Having thus described and explained my invention what I claim as new and desire to secure by Letters Patent is:

1. In a valve operating mechanism of the class described, a hollow member adapted to contain oil, and provided with an exterior bearing and an oil port leading thereto; a second member pivotally supported on said bearing and having an oil passage adapted to register at times with said oil port; an absorbent oil conveying member extending through said oil port; and a second absorbent oil conveying member in said passage and so positioned as to receive oil from said first absorbent member when the passage is in register with the oil port.

2. In valve operating mechanism of the class described and in combination, a hollow member adapted to contain oil, said member having an exterior bearing and an oil port leading thereto; a second member pivotally mounted upon the bearing of said hollow member and provided with a second bearing, and with a passage extending from one bearing to the other; absorbent oil conveying means extending through said oil port to the first mentioned bearing; and absorbent oil conveying means extending along said passage from said first bearing to said second bearing.

3. In valve operating mechanism, the combination with a hollow supporting member provided with an oil port; an oscillatory valve lever provided with a longitudinal passage adapted to communicate with the said oil port; an absorbent member extending through said port and adapted to convey oil to the surface of said supporting member; and an absorbent member in said passage and adapted and arranged to receive oil from said first mentioned absorbent member and to convey it along said passage.

4. In valve operating mechanism of the class described, an oscillatory valve lever; a hollow supporting member whereupon said lever is supported and which support-

ing member is provided with an oil port, and which lever is provided with a socket bearing at the free end thereof and with a longitudinally extending passage leading 5 from said oil port to said socket bearing; a reciprocating member provided with an enlarged head adapted to fit within said socket; and absorbent oil conveying means located within said passage and extending 10 from the supporting member aforesaid to said socket bearing.

5. In valve operating mechanism of the class described, an oscillating valve lever; a hollow supporting member provided with 15 an oil port, said lever being journaled upon said supporting member and also provided with a longitudinal passage and with a bearing at one end, said passage communicating with said bearing and with said port; 20 and absorbent oil conveying means extending from the interior of said supporting member through said port and along said passage, whereby oil may be fed by capillary action both to the lever supporting 25 bearing and to the end bearing.

6. In a valve operating mechanism of the class described, an oscillating valve operating lever, a hollow supporting member for supporting said lever, means for supplying 30 oil to the interior of said supporting member, an absorbent member for feeding oil from the interior of said supporting member to the bearing between the same and said valve operating lever, a reciprocating 35 operating member the upper end of which is in engagement with a bearing provided upon the under side of said valve operating lever, and a passage in said valve operating lever leading from said first mentioned 40 bearing to the bearing between the upper end of said operating member and said lever.

7. In valve operating mechanism of the class described, an oscillating valve operating lever, a hollow supporting member for supporting said lever, means for supplying 45 oil to the interior of said supporting member, an absorbent member extending from the interior of said supporting member 50 through a hole provided therein and lead-

ing to the bearing between said supporting member and said lever, a reciprocating operating member the upper end of which is in engagement with a bearing provided upon the under side of said valve operating lever, a passage leading from said first mentioned bearing to the bearing between the upper end of said operating member and said lever, and an absorbent member located within and extending along said passage. 55

8. In valve operating mechanism of the class described, a hollow supporting member adapted to contain oil, an oscillating valve operating lever supported by said supporting member and having a passage 60 leading from the bearing between the same and said supporting member to a second bearing provided upon the under side of said lever, an absorbent member located within, and extending along said passage, 65 and an absorbent member extending from the interior of said supporting member through a hole provided therein and which last mentioned absorbent member is adapted to supply oil to the bearing between said 70 supporting member and said valve operating member, and to the absorbent member within the passage aforesaid in said lever.

9. In valve operating mechanism of the class described, a hollow supporting shaft 80 adapted to contain oil, a plurality of oscillating valve operating levers supported by said shaft and having each a passage leading from the bearing between the same and said shaft to a second bearing provided 85 upon the under side of each lever, an absorbent member located within and extending along each of the passages aforesaid, and a plurality of absorbent members, one associated with the bearing of each of said 90 levers, extending from the interior of said shaft through holes provided therein and leading one to each of said bearings and which last mentioned absorbent members are adapted to supply oil to said bearings 95 and to the absorbent members located within the passages aforesaid.

In testimony whereof I affix my signature.

ENOS A. DE WATERS.
